UNITED STATES PATENT OFFICE.

MARTIN FISCHER, OF ZURICH, SWITZERLAND.

MOTOR-VEHICLE.

No. 834,283.

Specification of Letters Patent.

Patented Oct. 30, 1906.

Application filed March 1, 1906. Serial No. 303,625.

To all whom it may concern:

Be it known that I, MARTIN FISCHER, a citizen of Switzerland, residing at 307 Fortstrasse, Zurich V, Switzerland, have invented new and useful Improvements in Devices for Securing Motors in Motor-Vehicles, of which the following is a specification.

My invention relates to means for securing the motor to the frame of motor-vehicles, whereby the motor before being finally fixed is built into the frame of the vehicle with capability of swinging in order that the motor can be accurately and readily adjusted.

In building the motor into the vehicle-frame difficulty is experienced in bringing the motor exactly into the correct position relatively to the gearing. This difficulty is entirely overcome according to my invention.

The accompanying drawings illustrate two forms of construction of the invention.

Figure 1 is a section illustrating the first form; and Fig. 2 is a side elevation, parts being broken away, showing a modified form.

Referring first to Fig. 1, the two arms 3 of the motor-casing are formed with flanges 5, which lie against the angle-bars 2 of the vehicle-frame and are centrally drilled to receive screw-bolts 1. The bars 2 have like holes for the bolts, so that the motor at first hangs on the bolts 1 and can be swung about their axis. After the motor has been properly adjusted the flanges 5, motor-casing 3, and frame-bars 2 are all drawn tightly together by the nuts 4 of the bolts 1 being screwed up.

Referring now to the modification shown in Fig. 2, the two arms of the motor-casing are provided with trunnions or pins 11. These trunnions rest in stirrups 15, the threaded ends of which are passed through the bars 12 of the vehicle-frame and held there by nuts 14.

When the motor, which swings in the stir-

rips 15, has been accurately adjusted, the nuts 14 are tightened up, whereby the trunnions 11 are drawn firmly against the blocks 16, inserted between them and the bars 12. In this manner the motor is held fast without any danger of its shifting.

Having thus described my invention, what I claim as new, and desire to secure by Letters Patent of the United States, is—

1. In a motor-vehicle, the combination with a vehicle-frame, of a motor-casing having two lateral arms, means on the vehicle-frame from which the lateral arms can be at first loosely suspended to allow of the motor-casing being swung around its horizontal axis for the adjustment thereof in proper position relatively to the gearing, and by which after its adjustment, the said motor-casing can be rigidly secured to the vehicle-frame, substantially as and for the purpose specified.

2. In a motor-vehicle, the combination with a vehicle-frame, of a motor-casing having two lateral arms, stirrups adjustably secured in the vehicle-frame, said stirrups being adapted, at first, to loosely embrace the said arms of the motor-casing to permit of the latter being swung around its horizontal axis for adjustment thereof in proper position relatively to the gearing, and after the adjustment of the motor-casing to be tightened so as to rigidly secure the motor-casing to the vehicle-frame, substantially as and for the purpose specified.

In testimony whereof I have signed my name to this specification in the presence of two subscribing witnesses.

MARTIN FISCHER.
